United States Patent Office

Des. 216,297
Patented Dec. 16, 1969

216,297

DISPENSING CLOSURE

Roland E. Johnson, Cincinnati, Ohio, assignor to The Procter & Gamble Company, Cincinnati, Ohio, a corporation of Ohio

Filed Aug. 19, 1968, Ser. No. 13,183

Term of patent 14 years

Int. Cl. D9—02

U.S. Cl. D9—275

FIG.1

FIG.2

FIG.3

FIG.4

FIGURE 1 is a top plan view of a dispensing closure showing my new design.

FIGURE 2 is a side elevational view.

FIGURE 3 is an enlarged cross sectional view taken on the line 3—3 of FIGURE 1 but with the cover member partially open; and

FIGURE 4 is a front elevational view.

The side not shown is a mirror image of the side shown.

I claim:

The ornamental design for a dispensing closure, as shown and described.
